UNITED STATES PATENT OFFICE.

ROBERT D. GRAY, OF NEW YORK, N. Y.

APPARATUS FOR RECORDING MOTION AND SOUND.

1,384,612.

Specification of Letters Patent. Patented July 12, 1921.

Application filed August 4, 1920. Serial No. 401,178.

To all whom it may concern:

Be it known that I, ROBERT D. GRAY, a citizen of the United States, and a resident of the city of New York, borough of Manhattan, in the county and State of New York, have invented a new and Improved Apparatus for Recording Motion and Sound, of which the following is a full, clear, and exact description.

10 The invention relates to apparatus for producing a kinetoscopic or moving picture film and a sound record in synchronism.

15 The object of the invention is to provide a new and improved apparatus for recording motion and sound arranged to encompass a number of performers, say actors, speakers, singers, players of musical instruments or other sound producing media, distributed on a stage or other support for producing both 20 a kinetoscopic record and a sound record.

Another object is to provide a sound reflector capable of receiving the sounds from one or a plurality of sound producing media, to concentrate the same and to deliver the 25 concentrated sounds to a sound recorder to transcribe and record the meaning of the sounds for reproduction akin to the original sounds emanating from the actors, singers, musical instruments or other sound producing media.

30 Another object is to provide a reflector capable of picking up sounds, even the faintest, emanating from the sound producing media distributed across a stage, with practically equal intensity, and to transmit such picked-up sounds to the sound recorder.

Another object is to improve the recording of sounds, first, by providing a sound reflector having curved surfaces which have 40 one focus at approximately the same point within the sound reflector and the second focus at different points upon the stage thus allowing some latitude of movement to the actors; and, second, to provide a receiver 45 adapted to receive sounds over a considerable area in the neighborhood of the common focus point.

With these and other objects in view, the invention consists of certain novel features 50 of construction as hereinafter shown and described and then specifically pointed out in the claims.

A practical embodiment of the invention is represented in the accompanying drawings 55 forming a part of this specification, in which similar characters of reference indicate corresponding parts in all the views.

Figure 1 is a sectional side elevation of the improved apparatus for recording motion and sound;

60 Fig. 2 is a front elevation of the sound reflector viewed along the line 2—2 of Fig. 1;

Fig. 3 is a sectional plan view of the same on the line 3—3 of Fig. 1 and with the sound receiver and recorder omitted;

65 Fig. 4 is a similar sectional plan view of the same on the line 4—4 of Fig. 2;

Fig. 5 is an enlarged sectional side elevation of a modified form of the sound receiver;

70 Fig. 6 is a cross section of the same on the line 6—6 of Fig. 5;

Fig. 7 is an enlarged sectional side elevation of another modified form of the sound receiver; and

75 Fig. 8 is a cross section of the same on the line 8—8 of Fig. 7.

In recording sound for phonographic purposes as now generally practised the singers, speakers, players of musical instruments and like performers are located in close proximity to the mouth of a large horn for gathering the sounds and conducting the same to the diaphragm of a sound recording machine of usual construction. By this mode of recording sound considerable of the finer qualities and the naturalness and particularly the soft and melodious portions of the sounds produced by the performers are lost and not reproduced. On account of requiring crowding of the performers in front of the horn it is practically impossible to produce simultaneously satisfactory sound records and motion records of the performers especially the motion records owing to the absence of the free motions and actions of the players as usually witnessed, for instance, during a play, opera or other regular performances on the speaking stage, or as enacted silently by the moving picture actors and similar performers of the unspoken word.

90 The improved apparatus for recording motion and sound in its general construction comprises a stage 10, a sound reflector 11 in front of the stage 10, a sound receiver 12 located within the sound reflector 11 at the acoustic focus, a sound recorder 13 arranged outside of the sound reflector 11 and connected with the said sound receiver 12, and a moving picture camera 14 arranged outside of the sound reflector 11 but having its objective 15 arranged within the sound reflector 11, the said moving picture camera 14 being arranged to encompass 95 100 105 110

the scenery and players on the stage 10. The stage 10 is provided with the usual foot-lights 16 and the headlights 17 for properly illuminating the scenery and the performers 5 on the stage 10. The sound reflector 11 takes the place of the usual auditorium of a theater or hall. The sound reflector consists of a hollow body having an interior curvilinear surface formed of sound reflecting segments, 10 as hereinafter more fully explained. The base or mouth of the sound reflector body is disposed in a vertical plane coinciding with the front edge of the stage 10 and the said mouth joins the stake opening or pros- 15 cenium. The horizontal axis 20 of the sound reflector 11 extends a distance above the floor 21 of the stage 10, corresponding approximately to that of the height of an average person, and the performers on the 20 stage face the sound reflector 11 the same as they usually do an audience, so that the sounds emitted by the performers, or those emanating from the instrument played by the performers, pass into the sound reflector 25 11 to be reflected to the sound receiving means 12.

The sound reflecting segments of the sound reflector 11 comprise preferably two parabolic side segments 30, 31, top and bottom 30 elliptic segments 32, 33 and four corner elliptic segments 34, 35, 36 and 37. The parabolic and elliptic segments forming the inner surface of the sound reflector 11 are preferably formed of damped fiber bent 35 to the corresponding shapes and tacked to a suitable framework, or the segments may be formed of the usual lath and plaster. The edges of adjacent segments owing to their different curvature may not join through- 40 out their length but leave spaces between them which should be closed by thin walls disposed radially relative to the axis 20. The common foci of the sound reflecting segments 30, 31, 32, 33, 34, 35, 36 and 37 are at 45 the axis 20 of the sound reflector, and the said foci preferably coincide, as indicated in Figs. 1, 3 and 4. The other foci of the top and bottom elliptic segments 32 and 33 coincide at a point 40 located at the axis 20 at 50 the stage 10, the said axis 20 being the major axis of the elliptic segments 32 and 33. The major axes 41 and 42 of the corner elliptic segments 34, 36 and 35, 37 are in the horizontal plane of the axis 20 but di- 55 verge relative to the axis 20, and their other foci 43, 44 are located in a horizontal trans-verse line 45 passing through the point 40, and the said foci 43 and 44 are spaced equal distances from the point 40, as will be read- 60 ily understood by reference to Fig. 4. It will be noticed that by the arrangement de-scribed sounds coming from the stage into the sound reflector 11 and striking the side or parabolic segments 30, 31 are reflected by 65 the latter to the sound receiver 12 located

in the vertex of the sound reflector with its axis coinciding with the axis 20 and extending in the front and rear of the common foci of the sound reflecting segments. A parabola, having but one focus, is operative 70 only on waves traveling parallel with its major axis. In a stage performance the sounds emanate from a line across the stage at every point in a horizontal line, and since sounds from these points can be reflected to 75 the focus of a parabola only by a restricted segment of its surface, a horizontal segment, it follows that all sound waves produced by the actors that deviate materially from the horizontal, require a different curve than a 80 parabola, to focus them as desired. Therefore, the segments 32, 33 are made of elliptical form which reflect the sounds to the sound receiver 12, and the sounds coming from the stage toward the corners of the reflector 11 are reflected by the corner elliptic segments 34, 35, 36 and 37 to the sound receiver 12. Thus the various sounds coming from the different parts of the stage into the reflector 11 are concentrated at the focus 85 90 and are taken up by the sound transmitter and transmitted by the latter to the sound recorder 13 to be recorded thereon in their concentrated and intensified condition. Exact proportions and character of the reflecting segments may be modified in accordance with the breadth of the stage and to give predominance in intensity of sounds in the record from any particular part of the stage, or to equalize inherent differences of 100 loudness in voice or instrument. The drawings show a combination of segmental reflectors intended to give approximately equal emphasis in the records of sounds produced at all points on the stage line. 105

It is understood that a moving picture record is taken of the performers on the stage by the moving picture camera 14 which operates by a suitable mechanism (not shown) in synchronism with the sound recorder 13 thereby producing sound records and moving picture films which are in synchronism and can be reproduced as such. 110

The sound receiver 12 may be of various forms. As shown in Fig. 1, it consists of a 115 series of horns or funnels 50 having their common axis coinciding with the axis 20 of the sound reflector 11. The horns or funnels 50 are nested in spaced relation with their mouths 51 extending toward the stage. The rearmost horn or funnel has its shank 52 extending through the vertex of the sound reflector 11 and its outer end connects with the sound recorder 13. By reference to Fig. 1, it will be noticed that the 120 mouth edges of the several horns are gradually curved farther back to readily catch the sounds reflected forwardly from the vertex portion of the sound reflector 11. The several horns 50 encompass the acoustic 125 130

foci of the several reflecting segments 30 to 37 and hence none of the sounds passing into the sound reflector 11 is lost and even the faintest sounds are received and transmitted to the sound recorder 13.

The sound receiver 12, shown in Figs. 5 and 6, consists essentially of a tubular or cylindrical structure having its peripheral face formed of sets of segments 60 of aluminum or other stiff material attached to the outer forked ends of radial rods 61, terminating in balls or knobs 62 engaging the beveled peripheral faces of disks 63 attached to a central rod 64 coinciding with the axis 20. The rod 64 is mounted to slide in heads 65 and 66 forming part of a skeleton frame having the head 65 attached to the vertex part of the sound reflector 11. The heads 65 and 66 are connected with each other by rods 67 which support disks 68 extending between adjacent sets of segments 60. The disks 68 are provided with guide arms 69 for the radial rods 61, and the outer edges of the disks 68 are connected by flexible bands 70 with the adjacent edges of the sets of segments 60, and similar bands 71 and 72 connect the outermost and innermost sections 60 with the disk 66 and with a tube 73 forming part of the inner head 65 of the skeleton frame. The bands 70, 71 and 72 hold the segments 60 in spaced relation with each other and allow independent action of each segment 60. A spring 74 is coiled on the inner end of the rod 64 and abuts with one end on the disk 66 and presses with its other end on a nut 75 held on the end of the rod 64. The rear end of the rod 64 extends through an opening 76 at the vertex of the sound reflector 11 and this end connects with the sound recorder 13. It will be noticed that the sounds reflected by the sound reflector 11 strike the segments 60 and the force of the impact causes the segments 60 to move inward and in doing so the balls 62 pressing on the beveled edges of the disks 63 cause the latter and their rod 64 to move to the left against the tension of the spring 74, which latter returns the rod 64 and disks 63 to normal position as soon as the force 50 of the impact is spent. By the arrangement described the rod 64 is actuated by the reflected sounds and the latter are thus recorded on the sound recorder 13.

The modified sound receiver 12, shown in Figs. 7 and 8, consists essentially of a shell 80, polygonal in cross section and made of a flexible material such as oiled silk or like fabric. The shell 80 is stretched on rods 81 attached to the vertex portion of the sound reflector 11 and the forward end of the shell 80 is closed by a rigid disk 82 mounted on the rods 81. A diaphragm 84 within the shell 80 is in contact with the shell and is attached to a central rod 85 connected with the sound recorder 13. The vertex portion

of the sound reflector 11 is provided with an opening 86 in register with the shell 80 to prevent back pressure therein. It will be noticed that the sounds reflected by the sound reflector 11 strike a corresponding side of the shell 80 and the impact forces such side inward thus compressing the air within the shell between the diaphragm 84 and the solid head 82. The compressed air thus vibrates the diaphragm 84 correspondingly and the sound is recorded by the sound recorder 13 connected with the diaphragm by the rod 85.

It is expressly understood that the sound receiver 12 is located at the common focus 80 of the reflecting segments of the sound reflector 11, and each sound receiver is of sufficient length to extend forward and rearward beyond the focus to intercept or pick up sounds that come from other planes than that described by points 40, 43 and 44.

It is understood that the sound reflector 11 is of large dimensions, commensurate with that of the stage 10 of a theater of usual size, and by arranging the sound receiver as above set forth no particular or unusual vocal effort or positioning is required on the part of the performer or performers to insure proper recording of the sounds, at the same time the performer or performers can properly enact any desired scene on the stage, such scene being recorded by the moving picture camera 14 in synchronism with the recording machine 13.

Having thus described my invention, I claim as new and desire to secure by Letters Patent:

1. In an apparatus of the class described, a support for the sound producing media, a reflector in front of the said support and having its base facing the support, the said reflector being formed of elliptic and parabolic segments having one common focal point and certain of said segments having a common axis, and a sound receiver having its axis coinciding with said common axis of the reflector segments and having receiving means located at the said common focal point.

2. In an apparatus of the class described, a support for the sound producing media, a reflector in front of the said support and having its base facing the support, the said reflector being formed of elliptic segments having one common focal point and certain of said segments having a common axis, and a sound receiver having its axis coinciding with the said common axis of the reflector segments and being located at the said common focal point, the said support being arranged to support the sound producing media approximately at the other foci of the ellipses of which the said elliptic segments form parts.

3. In an apparatus of the class described,

a support for the sound producing media, a reflector in front of the said support and having its base facing the support, the said reflector being formed of elliptic segments 5 having one common axis, and a sound receiver having its axis coinciding with the said common axis, the said support being arranged to support the sound producing media approximately in a horizontal transverse line crossing the axis of the reflector approximately at the other focus of the ellipses of which the said elliptic segments form parts.

4. A sound reflector having its interior 15 surface formed of elliptic and parabolic segments having a common axis, the elliptic segments having a common acoustic focus located in the said common axis.

5. A sound reflector provided with elliptic 20 segments having one of their foci located within the reflector, and the other outside thereof, sundry of the said elliptic segments having the other foci outside of the reflector at a point in the said common axis and a distance 25 from the base of the reflector, and the other elliptic segments having the other foci of their ellipses in a horizontal line intersecting the common axis at the said point, the said other foci being spaced approximately 30 equal distances from the said point.

6. A sound reflector having its interior surface formed of segments, of which the side segments are parabolic and the top, bottom and corner segments are elliptic, the said 35 elliptic segments having a common focus located within the reflector, the top and bottom elliptic segments having the other foci of their ellipses coinciding at a point a distance outward from the base of the reflector, 40 and the said elliptic corner segments having the other foci of their ellipses located in a horizontal line intersecting the common axis at the said point, the said other foci of the corner segments being spaced approximately 45 equal distances from the said point.

7. In an apparatus of the class described, a stage having a floor adapted to support sound producing media ranging in a transverse line a distance above the floor, a sound 50 reflector arranged in front of the said stage and having its base in a vertical plane at the front of the stage, the said sound reflector being formed of segments of which the side segments are parabolic and the top, 55 bottom and corner segments are elliptic, the said top, bottom and side segments having a common horizontal axis intersecting said horizontal stage line at a right angle, the said elliptic segments having their foci at 60 the said axis within the reflector, the top and bottom elliptic segments having their other foci at the intersection of the said axis and the transverse stage line, the said corner elliptic segments having the other 65 foci of their ellipses at the said stage line at

opposite sides of the said point of intersection and spaced therefrom, the said parabolic segments having their focus at the common axis within the reflector, a sound receiver having receiving means encompassing both foci of the said elliptic and parabolic segments, and a sound recording instrument located outside of the reflector and connected with the said sound receiver at the vertex of the reflector. 75

8. In an apparatus of the class described, a stage having a floor adapted to support sound producing media ranging in a transverse line a distance above the floor, a sound reflector arranged in front of the said stage 80 and having its base in a vertical plane at the front of the stage, the said sound reflector being formed of segments of which the side segments are parabolic and the top, bottom and corner segments are elliptic, the said top, bottom and side segments having a common horizontal axis intersecting said horizontal stage line at a right angle, the said elliptic segments having their foci at the 85 said axis within the reflector, the top and bottom elliptic segments having their other foci at the intersection of the said axis and the transverse stage line, the said corner elliptic segments having the other foci of their ellipses at the said stage line at opposite sides of the said point of intersection and spaced therefrom, the said parabolic segments having their focus at the common axis within the reflector, a sound receiver having receiving means encompassing both 90 foci of the said elliptic and parabolic segments, and a sound recording instrument located outside of the reflector and connected with the said sound receiver at the focus near the vertex of the reflector. 95

9. In an apparatus of the class described, a support for sound producing media, a reflector in front of the said support and having its base facing the support, the said reflector being formed of segments of conic 100 sections having one common focus and certain of said segments having a common axis, others of said segments having their axes disposed at an angle to the said common axis, and a sound receiver located at the said 105 common focus.

10. A sound reflector having its interior surface formed of segments of conic sections having one common focus located within the reflector, the top and bottom segments 110 having their other foci coinciding at a point a distance outward from the base of the reflector, and the said corner segments having the other foci located in a horizontal line intersecting the common axis at the said 115 point, the said other foci of the corner segments being spaced approximately equal distances from the said point.
